DIE CONSTRUCTION

Edwin A. Bierwirth, Detroit, Mich., assignor to
Kelsey-Hayes Wheel Company, Detroit, Mich.,
a corporation of Delaware

Application August 3, 1936, Serial No. 94,107

7 Claims. (Cl. 164--86)

The invention relates to die constructions and refers more particularly to die constructions for piercing brake drums and the like to adapt the same for securement to wheel hubs.

5 It is essential that a brake drum when assembled upon a wheel hub have its braking surface truly concentric with the axis of the wheel hub. It is therefore essential that the brake drum have its holes, which are used in positioning 10 the brake drum, accurately located.

The invention has for one of its objects to provide a piercing die construction which will accurately position the brake drum or the like prior to the piercing to thereby accurately pierce 15 this element. The invention has for another of its objects to accurately position a brake drum or the like having an annular flange with reference to a surface of the flange prior to the piercing operation. The invention has for a further object to support the brake drum or the like in the zone of its flange to thereby avoid distortion of 20 the web. The invention has for these as well as other objects the novel arrangement and combinations of parts as more fully hereinafter set forth.

25 In the drawings:

Figure 1 is a plan view, with part of the carrier removed, of a die construction showing an embodiment of my invention;

30 Figure 2 is a cross section on the line 2--2 of Figure 1 including the part of the carrier removed from Figure 1; and

Figure 3 is a cross section on the line 3--3 of 35 Figure 1.

35 As illustrated in the present instance, the die construction comprises the base 1 and the carrier 2, the latter being movable toward and away from the former and being guided with respect thereto by means of the pilot rods 3 at opposite sides 40 of the die construction. 4 are cylinders mounted upon the base 1 at diagonally opposite corners and 5 are pistons within these cylinders and fixed upon the upper ends of the piston rods 6, the lower ends of which are fixedly secured to the 45 diametrically opposite arms 7' of the plate 7. This plate is located above the base and freely encircles the central upwardly extending annular projection 8 integral with the base. The base is preferably recessed to receive the plate with 50 its arms.

In the present instance, I have illustrated the die construction operable upon the brake drum 9, this brake drum being composite and having the annular brake flange 10 and the web 11, the 55 web being formed of sheet metal and the brake

flange being formed of a casting imbedding the peripheral portion of the web.

12 is an annular positioning member fixedly mounted upon the base 1 and having the tapered portion 13 extending upwardly from its base 13', the inner surface of this tapered portion being cylindrical and the outer surface being tapered upwardly and toward the axis of the positioning member. 14 is a support engageable with the free end of the brake flange 10, this support being fixedly mounted on the base 1 and, as shown in the present instance, being fixedly secured upon the base 13' of the positioning member 12. The upper end of the support 14 is located below the upper end of the tapered portion 13. 15 is a second annular positioning member having the upper tapered portion 16, the taper of this portion being downward and toward the axis of the positioning member. The positioning member 15 has the lower cylindrical portion 16' sleeved within the positioning member 12 and fixedly secured to the plate 7. The positioning member 15 is guided by the central pilot 17 fixedly secured to the central projection 8 of the base and extending upwardly therefrom. The arrangement is such that the two positioning members and the pilot are concentric. 18 is a positioning member adapted to cooperate with the positioning members 12 and 15 and comprising a transversely split resilient ring engageable with the internal braking surface of the brake flange 10. This ring has at its opposite edges the upper and lower flanges 18' and 18" respectively which extend radially inwardly and the free edges of which are preferably formed with notches in angularly spaced zones to increase the flexibility of the ring. The outer surface of the web of the ring is also notched in angularly spaced zones for the same purpose. The inner edges of the upper and lower flanges are preferably tapered in accordance with the tapers of the portions 16 and 13 respectively to provide a substantial contact. The ring is preferably held from bodily rotation by means of the key 19 between the lower flange 18" and the tapered portion 13 of the stationary 45 positioning member 12.

The central pilot 17 has fixedly secured to its upper end the annular die 20 having an internal diameter slightly less than that of the pilot and the annular series of annular dies 21 positioned 50 radially outwardly of the die 20. These dies are fixed in a predetermined relation to the axes of the tapered members 12 and 15, the annular die 20 and the annular series of dies 21 being exactly concentric therewith. The carrier 2 carries the 55

central punch 22 and the annular series of punches 23 which are adapted to cooperate with the central die 20 and the annular series of dies 21 respectively to pierce the web 11 of the brake drum and to form the central hole 24 and the annular series of holes 25. The central hole 24 enables passing the brake drum over a portion of the wheel hub and the holes 25 are adapted to receive the securing means, such as bolts or studs used in securing the brake drum to the wheel hub. Both the holes 24 and annular series of holes 25 are accurately positioned with respect to the internal braking surface of the brake drum and assuming that the hub is accurately formed, the 15 brake drum when mounted upon the hub will be accurately centered and secured thereto. The carrier 2 also carries the pressure plate 26 which is normally urged downwardly by the coil springs 27. This pressure plate yieldably holds the web 20 11 of the brake drum against the dies 20 and 21 during the piercing operation.

In operation and assuming the carrier 2 to be in raised position and the positioning member 15 also in raised position, the ring 18 by reason 25 of its inherent resiliency will be in a contracted position as permitted by the tapered surfaces of the positioning members 15 and 12. At this time the ring will be slightly elevated above the position shown in Figure 2. After the brake drum 30 has been inserted into place to rest upon the annular support 14, suitable fluid under pressure, such as compressed air, may be admitted to the upper ends of the cylinders 4 to lower the pistons 5 and to thereby lower the positioning member 15 35 through the intermediary of the piston rods 6 and the plates 1. The lowering of this member causes expansion of the ring 18, both by reason of its tapered surface and also the tapered surface of the stationary positioning member 12. 40 As a result, the ring is expanded at both its upper and lower edges and upon complete engagement with the brake flange 10 of the brake drum positively centers this brake drum. Then with the parts in these positions, the carrier 2 is lowered, 45 thereby piercing the central pilot hole 24 and the holes 25 for receiving the securing means, all of these holes being accurately positioned with respect to the braking surface of the brake flange.

What I claim as my invention is:

50 1. In a die construction for piercing the web of an element having an annular flange, the combination with a transversely split resilient ring engageable with the annular flange, oppositely tapered members engageable with the opposite edge portions of said ring, said members being concentric and relatively movable in opposite directions to move said ring against the annular flange to thereby position the latter, and cooperating means having a predetermined relation to the axes of said tapered members for piercing the web.

55 2. In a die construction for piercing the web of an element having an annular flange, the combination with a transversely split resilient ring engageable with the annular flange, oppositely tapered annular members engageable with the opposite edge portions of said ring, said members being concentric and relatively movable axially in opposite directions to move said ring against the annular flange to thereby position the latter, and cooperating members relatively movable axially in opposite directions to pierce the web, said members having a predetermined relation to the axes of said tapered members.

60 3. In a die construction for piercing the web

of a brake drum having an annular brake flange with an internal braking surface, the combination with a transversely split resilient ring within the brake drum and engageable with the braking surface, oppositely tapered members extending within said ring and engageable with the opposite edge portions thereof, said members being concentric and relatively movable axially in opposite directions to move said ring against the braking surface to thereby position the brake drum, and cooperating means having a predetermined relation to the axes of said tapered members for piercing the web.

4. In a die construction for piercing the web of a brake drum having an annular brake flange with an internal braking surface, the combination with a transversely split resilient ring engageable with the annular flange, a stationary tapered member extending within said ring and engageable with one edge portion thereof, an axially movable tapered member extending within said ring and engageable with the other edge portion thereof, said tapered members being concentric and one being guided by the other, a support fixed with respect to said stationary tapered member and engageable with an end of the brake flange, and cooperating members having a predetermined relation to the axes of said tapered members for piercing the web.

5. In a die construction for piercing the web of a brake drum having an annular brake flange with an internal braking surface, the combination with a base having a central pilot, a transversely split resilient ring within the brake drum and engageable with the braking surface, a tapered member supported upon said base and extending within said ring and engageable with an edge portion thereof, said tapered member being concentric with said pilot, a member fixed with respect to said base and engageable with an end of the brake flange to support the brake drum, a second tapered member guided by said pilot and engageable with the other edge portion of said ring, means for axially moving said second mentioned tapered member with respect to said first mentioned tapered member, die means upon said pilot and engageable with the web, and punch means cooperable with said die means for piercing the web.

6. In a die construction for piercing the web of an element having an annular flange, the combination with an expansible and contractible member engageable with the annular flange, tapered positioning members engageable with said first mentioned member, said positioning members being concentric and relatively movable to move said first mentioned member against the annular flange to thereby position the latter, and cooperating means having a predetermined relation to the axes of said positioning members for piercing the web.

7. In a die construction for piercing the web of an element having an annular flange, the combination with a base having a central pilot, an expansible and contractible member within the element and engageable with the annular flange, relatively movable positioning members carried by said base and concentric with said pilot, said piercing members being engageable with said expansible and contractible member, die means upon said pilot having a predetermined relation to the axes of said positioning members, and punch means cooperable with said die means for piercing the web of the element.

EDWIN A. BIERWIRTH. 75
